The ornamental design for a batting tee adapter, as shown and described.

DESCRIPTION

FIG. 1 is a perspective view of a batting tee adapter showing our new design.

FIG. 2 is a front elevation view thereof.

FIG. 3 is a rear elevation view thereof.

FIG. 4 is a right side elevation view thereof; the left side elevation view being a mirror image thereof.

FIG. 5 is a top plan view thereof.

FIG. 6 is a bottom plan view thereof; and,

FIG. 7 is a front elevation view thereof including environmental structure.

The broken lines represent portions of the batting tee adapter and environmental structure that form no part of the claimed design.
